PICTURE FRAME

John Niver Seism, Baltimore, Md.

Application May 12, 1947, Serial No. 747,511

6 Claims. (Cl. 40—156)

1

This invention relates to decorative ornaments and particularly to a picture holder of durable construction provided with a supporting member which not only supports a picture, surrounded by a decorative frame, but enables the picture to be arranged at various angles so that it can be most effectively observed regardless of whether it be placed in an elevated position in a room, such as on a mantelpiece, or upon a low table.

Therefore an object of this invention is to provide a picture holder having a supporting member which holds the picture in place within a decorative border or frame and tilted at the correct angle for proper observation.

The above and additional advantages and features of the invention are described and claimed in the following specification and claims and are illustrated in the accompanying drawing, in which:

Figure 1 is a cross-sectional elevation of the picture holder of this invention;

Figure 2 is a plan view of the base;

Figure 3 is a front view of the decorative border with the supporting member attached;

Figure 4 is a cross-sectional view taken on the line 4—4 of Figure 1;

Figure 5 is a detailed fragmentary cross-section of a modified form; and

Figure 6 is an elevational view of a modified form of clamp, shown partly in cross-section.

Referring now to the drawing in detail, the decorative border or frame of the picture holder is indicated by the reference numeral 7 in the central portion of which there has been provided a recess having a shoulder 9 and an inwardly extending wall 1a from which projects a short flange 8 at substantially right angles to the wall 1a. In the preferred embodiment of the invention, the border or frame is made of a single piece of stamped metal, but it is to be understood that any suitable material may be used, such as plastic, or other material formed in the manner shown. Furthermore, the frame is shown in the shape of an oval, but it may be rectangular, or irregularly shaped if desired. Similarly, while the recessed portion is shown in oval shape, it may be rectangular, or irregularly shaped.

The picture which it is desired to place in the holder is indicated by the reference numeral 10, and is fitted into the recessed portion. A thin layer of any resilient material 11, such as felt, may be placed between the picture and the flange 8 to constitute a rear mat or backing for the picture. A marginal mat or border 12 of conventional pattern may be placed in front of the pic-

2

ture, and a suitable piece of glass 13, or other transparent material may be placed over the mat 12. A clamp 14, constituting a front clamping ring and shaped to fit within the recessed portion of the border 7 when suitably secured in place, holds the picture 10, with its felt backing 11, mask 12, and glass 13 within the recess. The felt backing 11 also equalizes the pressure of the flange 8 against the picture.

10 A supporting member 15, made of a strip of flat metal preferably, fits against the back of the inwardly extending flange 8. The clamp 14 is provided with threaded holes 16 to receive the bolts 17. Openings are also provided in the glass 13, mask 12, picture 10, felt backing 11, flange 8, and supporting member 15, in alignment with the holes 16, to allow passage of the bolts 17. When the device is assembled the heads of the bolts 17, bearing against the supporting member 15 will draw up the clamp 14 to press against the intervening elements, thus holding the border 7, and the picture 10, in place.

15 A base 18 is provided with pads 19 made of a soft material, such as neoprene or felt, so as not to scratch or mar surfaces upon which the base may rest. The base may be formed of a single piece of stamped metal, and is provided with an arcuately shaped depression 20 in its upper surface. In a threaded hole 18a at the bottom of this depression is fitted the threaded shank 21 of a vertically projecting thumb screw and which thumb screw has a knurled head portion 24. Formed integrally with the supporting member 15 is a backwardly extending arcuate leg 22 which is shaped to cooperate with the arcuately shaped depression 20, and enables the border to be tilted forward and back to provide the proper angle for viewing the picture. A slot 23 is cut in the arcuate leg in a lengthwise direction to accommodate the shank 21 of the thumb screw. In this relation the head 24 bears against the top surface of the arcuate leg 22 to position it in the depression 20.

20 A modified form of clamp is shown in detail in Figure 5. In this case, the clamp 14 is recessed at its sides at 14a and is thus spaced from the adjacent retaining wall of the frame. When the clamp is drawn up by the bolts 17 the rim 25 abuts against the shoulder 9 of the border 7, and prevents excessive pressure being applied to the picture 10 and its associated elements 11, 12, and 13. Furthermore, the recessed portion 14a enables the clamp to readily adapt itself to an easy adjustment within the frame.

25 Still another form of clamp is shown in Fig-

ure 6. As can be seen, this form of clamp is substantially U-shaped in cross-section, with the base 26 of the U forming the inner portion of the clamp, while the arms of the U provide outwardly extending flanges 27, and 28, at the front and the back, respectively, of the clamp. Threaded holes 16 for the bolts 17 are provided only in the back flange 28 so that when the clamp is in place the front flange 27 will present a smooth and pleasing appearance to the eye.

A flat strip of metal 29 is attached, by spot welding or other means, to the back of the border 7 near the top. The ends of the strip are turned back and provided with holes to form the ears 30. If desired, the base 18 may be removed from the support by removing the thumb screw 21, in which case the picture holder may be hung from a hook on a wall by means of a wire strung through the ears 30.

I claim:

1. A picture holder comprising in combination, a frame provided with a recessed portion having an inwardly extending flange extending transversely of said recessed portion and adapted to receive a display sheet, a clamp fitting within said recessed portion in front of said display sheet, a supporting member adapted to fit the back of said flange, adjustable securing means extending through said supporting member said flange and at least a portion of said clamp to hold said frame and said display sheet in place upon said supporting member.

2. A device of the character disclosed in claim 1 in which a resilient backing material is provided between said clamp and said flange to equalize the pressure exerted by said flange against the display sheet.

3. A picture holder comprising in combination, a frame provided with a recessed portion, the front portion of said recess forming a shoulder and the rear portion of said recess having an inwardly extending flange extending transversely of said recessed portion and adapted to receive a display sheet, a clamp fitting within the recessed portion of said border in front of the display sheet, the front of said clamp being

provided with a laterally extending rim adapted to abut against said shoulder, means threaded in said clamp and extending through said supporting member said flange and at least a portion of said clamp to hold said frame and the display sheet in place upon said supporting member.

5. A device of the character disclosed in claim 3 in which a resilient backing material is provided between said clamp and said flange to equalize the pressure exerted by said flange against the display sheet.

15 6. A picture holder having a tiltably positionable base comprising in combination, a frame provided with a recessed portion having an inwardly extending flange extending transversely of said recessed portion and adapted to receive a display sheet, a clamp provided with spaced laterally extending flanges at the front and at the back and fitting within the recessed portion 20 of said frame in front of said inwardly extending transverse flange, a supporting member adapted to fit the back of the inwardly extending flange in said recess, securing means threaded in the back flange of said clamp and 25 extending through said supporting member and said transversely extending flange to hold said frame and the display sheet in place upon said supporting member.

30 7. A device of the character disclosed in claim 5 in which a resilient backing material is provided between said clamp and said inwardly extending flange to equalize the pressure exerted by said flange against the display sheet.

JOHN NIVER SCISM.
